(57) CLAIM

What is claimed is the ornamental design for a light fixture, as shown and described.

DESCRIPTION

FIG. 1 is a front view of the light fixture of the invention. FIG. 2 is a right side view of the light fixture of FIG. 1. FIG. 3 is a left side view of the light fixture of FIG. 1. FIG. 4 is a rear view of the light fixture of FIG. 1; and, FIG. 5 is a top view of the light fixture of FIG. 1. The bottom view of the light fixture of FIG. 1 would be identical to or a mirror image of the top view of FIG. 5, and has therefore been omitted from the drawings. The broken lines shown in FIGS. 1 through 5 are for illustrative purposes only and form no part of the claimed design.
